(57) CLAIM

The ornamental design for a heart shaped tray, as shown and described.

DESCRIPTION

FIG. 1 is a top perspective view from above of a heart shaped tray;

FIG. 2 is a bottom perspective view thereof;

FIG. 3 is a front side thereof;

FIG. 4 is a back side thereof;

FIG. 5 is a side view thereof, for which the opposite side is a mirror image of;

FIG. 6 is a further top view thereof; and,

FIG. 7 is a bottom view thereof.

The portions of the tray shown in regular broken lines including the round recesses visible from the bottom views form no part of the claimed design.

1 Claim, 5 Drawing Sheets
